EGG CASE

Henry M. Nelson, Minneapolis, Minn.

Application May 25, 1951, Serial No. 228,260

11 Claims. (Cl. 229—27)

1

My invention relates to improvements in egg cases and has for an object thereof to provide a simple, durable, sturdy, relatively inexpensive and oft reusable knockdown egg case having two compartments for the accommodation of conventional egg case fillers and flats, the same being adapted to be quickly and easily folded into form of use from a single blank of sheet material and to be quickly and easily unfolded into its original form as a blank.

Other objects of the invention reside in the novel combination and arrangement of parts and in the details of construction hereinafter illustrated and/or described.

In the drawings:

Fig. 1 is a perspective view of an egg case constructed in embodiment of my invention.

Fig. 2 is a longitudinal central sectional view of the structure shown in Fig. 1, a portion of said structure being shown fragmentarily.

Fig. 3 is a detail sectional view taken as on the line 3—3 of Fig. 2.

Fig. 4 is a plan view of a blank of sheet material as used in producing an egg case of the construction shown in Fig. 1.

Fig. 5 is a perspective view illustrating a partial development of the blank shown in Fig. 4.

Fig. 6 is a perspective view similar to Fig. 5 illustrating further development of said blank.

Reference being had to the accompanying drawings, it will be understood that my improved egg case is produced from a single blank X stamped from any suitable sheet material such as fibre board, corrugated board or the like. This blank X includes a bottom panel 10 and also side panels 11 adapted to be folded upwardly from the bottom panel 10 along lines 12. One side panel 11 has a relatively long extension A at one end thereof, the other end of the other side panel 11 having a similar long extension A. At the end of each side panel 11 opposite the end thereof having the relatively long extension A is a relatively short extension B. Each long extension A includes an inner end panel 13 folded from its respective side panel 11 on line 14 crosswise of the bottom panel 10, an inner side panel 15 folded from said inner end panel 13 on the line 16 lengthwise of said bottom panel 10 and a cross-panel 17 folded from said inner side panel on line 18 crosswise of the bottom panel 10 midlength thereof. The inner end panel 13, the inner side panel 15 and the cross-panel 17 of each of the relatively long folded extensions A combine with the corresponding end portion of their respective side panel 11 to define one of the two compartments Y of the egg case. With said

2

long extensions A folded to define said compartments Y, the cross-panels 17 thereof stand juxtaposed face to face. Each of said relatively long extensions A further includes an inner bottom panel 19 for its respective compartment Y, the same being folded from the cross-panel 17 on line 20 lengthwise of the bottom panel 10.

Each short extension B constitutes an intermediate end panel 21, the same being folded from its respective side panel 11 on line 22 into position against the inner end panel 13 of its corresponding compartment Y.

The bottom panel 10 has extensions C at its opposite ends, each thereof including an outer end panel 23 folded up on line 24 from said bottom panel 10 into position against the intermediate end panel 21 of the corresponding compartment Y, a cover panel 25 for such compartment folded on line 26 from said outer end panel 23 lengthwise of the bottom panel 10, and an end or latching flap 27 folded down on line 28 from said cover panel 25 and adapted to be tucked in between the juxtaposed cross-panels 17.

Each end portion of each side panel 11 has a cover flap 29 thereon folded inwardly therefrom on a line 30. Similar cover flaps 31 and 32 on the inner end panel 13 and cross-panel 17, respectively, of each compartment Y are inwardly folded on lines 33, 34, respectively. The two cover flaps 29 on corresponding end portions of the side panels 11 and the cover flaps 31, 32 on the inner end panel 13 and cross-panel 17 of the corresponding compartment Y are adapted to be superimposed by the cover panel 25 for that compartment.

Each cross-panel 17 has a partial cut-out d consisting of two spaced vertical slits 35 which at the corresponding ends thereof meet a horizontal slot 36. In one cross-panel 17, the slot 36 is at the lower ends of the slits 35 thereby forming a depending tongue 37 and in the other cross-panel 17, the slot 36 is at the upper ends of the slits 35 thereby forming an upstanding tongue 37. The two cut-outs d in said cross-panels 17 register with each other and the tongues 37 thereof are bent out into reversely overlapping relationship, the tongue 37 of each cross-panel 17 extending into the cut-out d of the other cross-panel 17 and releasably interlocking the two cross-panels against relative movement transversely of the bottom panel 10.

Likewise, the inner end panel 13 and the companion intermediate end panel 21 for each compartment Y are each formed with a partial cut-out e consisting of two spaced vertical slits 38

which at the corresponding ends thereof meet a horizontal slot 39. In the inner end panel 13, the slot 39 is at the upper ends of the slits 38 thereby forming an upstanding tongue 40, while in the companion intermediate end panel 21, the slot 39 is at the lower ends of the slits 38 thereby forming a depending tongue 40. The two cut-outs e in companion inner and intermediate end panels 13, 21 register with each other and the tongues 40 thereof are bent out into reversely overlapping relationship. With said tongues 40 thus relatively disposed the tongue 40 of each of said intermediate end panels 21 extends into the cut-out e of its companion inner end panel 13, while the tongue 40 of each inner end panel 13 extends into the cut-out e of its companion intermediate end panel 21, thereby releasably interlocking said companion inner end panels 13 and intermediate end panels 21 together against relative movement transversely of the bottom panel 10.

The outer end panel 23 and the companion intermediate end panel 21 for each compartment Y are each formed with a horizontally extending hand-hole 41, the one being in registry with the other. The companion inner end panel 13 for the same compartment Y has a partial cut-out f therein registering with said registering hand-holes 41, said cut-out consisting of a horizontal slit 42 and two relatively spaced upwardly converging slits 43 forming an outwardly flared depending tab 44. This tab 44 is adapted to be folded out through the registering hand-holes 41 against the upper surfaces thereof, said tab so folded constituting a handpiece for the comfort of a user in lifting the case with his hand inserted into said registering hand-holes 41 and cut-out f. The distance along the wide free edge of each hand-piece tab 44 is slightly greater than the lengths of the registering hand-holes 41 of the companion intermediate end panel 13 and outer end panel 23 through which said flap 44 is forced upon the folding thereof into position within said hand-holes 41. Thus, the hand-piece tab 44 for each compartment Y releasably interlocks together in dovetail fashion the corresponding inner, intermediate and outer end panels 13, 21 and 23.

The hand-holes 41 additionally serve as ventilating openings in the case and, together with registering ventilating openings 45 in the cross-panels 17, provide for the circulation of air through the two compartments Y from end to end of the case.

Features which notably contribute to the sturdiness of the present article are the three thicknesses of sheet material at each end of the case provided by the inner end panel 13, intermediate end panel 21 and outer end panel 23; the two thicknesses of sheet material at the sides of the case in staggered relation provided by the inner side panel 15 for each compartment and the corresponding end portion of one of the side panels 11; the two thicknesses of sheet material at the bottom of the case provided by the inner bottom panel 19 folded from the cross-panel 17 of each compartment Y together with the corresponding portion of the bottom panel 10 of the case; the strengthening of each cross-panel 17 at its lower portion by folding its respective inner bottom panel 19 therefrom; the inwardly turned cover flaps 32 on said cross-panels 17 and the similar flaps 31 on the inner end panels 13 which reinforce their respective members at the upper portions thereof; and the inwardly turned cover flaps 29 on the side panels 11 which

strengthen said side panels 11 at their upper portions and augment the cover panels 25 in closing their respective compartments Y of the case.

The present egg case, strengthened at critical portions thereof as aforesaid, is capable of being stacked relatively high, case on case, for economy in shipping and storage space. Formed from a single blank, the case may be quickly and easily set up and knocked down, such facility thereof coupled with the strength of its construction, making many reuses of the case possible and conveniently practicable. The single blank from which the case is formed requires a minimum amount of material with relatively little waste in the cutting thereof.

Changes in the specific form of the invention, as herein described, may be made within the scope of what is claimed without departing from the spirit of the invention.

Having described the invention, what is claimed as new and desired to be protected by Letters Patent is:

1. A double-compartment egg case formed of sheet material providing an oblong bottom panel 25 and side panels folded up therefrom, each side panel having a relatively long extension at one end thereof and a relatively short extension at the other end thereof, the long extension of one side panel and the short extension of the other side panel being at corresponding ends of said side panels, each long extension including an inner end panel folded from its respective side panel crosswise of the bottom panel, an inner side panel folded from said inner end panel lengthwise of the bottom panel and a cross-panel folded from said inner side panel crosswise of said bottom panel midlength thereof, the inner end panel, the inner side panel and the cross-panel of each of said folded long extensions combining with the corresponding end portion of their respective side panel to define one of the two compartments of the egg case, the cross-panels of said long extensions being juxtaposed face to face, each short extension constituting an intermediate end panel folded from its respective side panel against the inner end panel of its corresponding compartment, said bottom panel having extensions at its opposite ends, each thereof including an outer end panel folded up from said bottom panel against the intermediate end panel of its corresponding compartment, and a cover panel for such compartment folded from said outer end panel lengthwise of the bottom panel.

2. The combination according to claim 1 wherein each extension of the bottom panel further includes a latching flap folded down from the cover panel thereof and adapted to be tucked between the two cross-panels of the two compartments.

3. The combination according to claim 1 wherein each relatively long extension of each side panel further includes an inner bottom panel folded from the cross-panel longitudinally of the bottom panel.

4. The combination according to claim 1 wherein each of the side panels is provided along its upper edge at each end portion thereof with an inwardly folded cover flap, said cover flaps on corresponding end portions of the side panels being adapted to be superimposed by the cover panel for the corresponding compartment.

5. The combination according to claim 1 wherein each of the side panels is provided at its upper edge at each end portion thereof with an

inwardly folded cover flap and each inner end panel and each cross-panel is provided at its upper edge with a similar inwardly folded cover flap, the cover flaps on corresponding end portions of the side panels and the cover flaps on the inner end panel and cross-panel included in the corresponding compartment being adapted to be superimposed by the cover panel for that compartment.

6. The combination according to claim 1 wherein means are provided for interlocking the juxtaposed cross-panels together to deprive them of relative movement transversely of the bottom panel.

7. The combination according to claim 1 wherein one cross-panel has a partial cut-out therein forming a depending tongue and the other cross-panel has a partial cut-out therein forming an upstanding tongue, each tongue being adapted reversely to overlap the other and extend into the cut-out thereof thereby to interlock said cross-panels together against relative movement transversely of the bottom panel.

8. The combination according to claim 1 wherein means are provided for fastening each inner end panel to its companion intermediate end panel thereby to deprive them of relative movement transversely of the bottom panel.

9. The combination according to claim 1 wherein each inner end panel has a partial cut-out therein forming a depending tongue and the

companion intermediate end panel has a partial cut-out therein forming an upstanding tongue, each of said tongues being adapted to overlap the other and extend into the cut-out thereof thereby to interlock such inner end panel and intermediate end panels against relative movement transversely of the bottom panel.

10. The combination according to claim 1 wherein each outer end panel and its respective intermediate end panel have registering hand-holes therein and its respective inner end panel has a partial cut-out therein forming a depending tab constituting a hand-piece, said tab being adapted to be folded out through said registering hand-holes against the upper surfaces thereof.

11. The combination according to claim 10 wherein the tabs are outwardly flared and interfit with their respective hand-holes in dove-tail fashion interlocking together their respective inner, intermediate and outer end panels.
